ROBE OR SIMILAR ARTICLE

Albert Wilson, Yonkers, N. Y., assignor to Richard Zelen, Port Chester, N. Y.

Application January 5, 1952, Serial No. 17,960

Term of patent 14 years

(Cl. D3—26)

To all whom it may concern:

Be it known that I, Albert Wilson, a citizen of the United States, residing at Yonkers, New York, have invented a new, original, and ornamental Design for a Robe or Similar Article, of which the following is a specification, reference being had to the accompanying drawings, forming part thereof.

Fig. 1 is a front view of a robe or similar article, showing my new design.

Fig. 2 is a rear view of the robe or similar article showing my new design.

The characteristic feature of my design resides in the combination on the quilted robe disclosed of the specific ribbed collar member which matches the cuffs and shaped pocket flap in texture, all as shown.

I claim:

The ornamental design for a robe or similar article, as shown and described.

ALBERT WILSON.
